UNITED STATES PATENT OFFICE.

HARRISON H. BOYCE, OF FOREST HILLS, NEW YORK.

TEMPERATURE-INDICATOR FOR AUTOMOBILES.

1,373,859.

Specification of Letters Patent.

Patented Apr. 5, 1921.

Application filed March 29, 1916. Serial No. 87,423.

To all whom it may concern:

Be it known that I, HARRISON H. BOYCE, a citizen of the United States, residing at Forest Hills, county of Queens, city and State of New York, have invented certain new and useful Improvements in Temperature-Indicators for Automobiles, of which the following is a specification.

This invention relates to means for indicating the thermal condition of automobile engines and the like, and particularly to means for indicating the temperatures within the radiators of water cooled internal combustion engines. As is well known, a great majority of automobiles are equipped with internal combustion engines which include a water cooling system and a radiator, the latter being usually placed at the front end of the car. Such radiators are commonly provided with filler spouts, which project upwardly from the top of the radiator, the upper end of the spout being closed by a suitable removable cap. The present invention provides means for inserting a temperature indicating instrument into the radiator, adjacent to the filler spout, either inside or outside thereof, so located with relation thereto as to be protected in some degree at least by the spout. The location of the instrument adjacent to the spout also provides a construction which is attractive in appearance, and the unsightly effect which would be produced if the instrument were located in a part of the radiator remote from the spout is avoided. The nature and more specific objects of the invention will appear from the following detailed description of certain preferred embodiments of the invention.

In the accompanying drawings which form a part of this specification, Figure 1 shows the upper part of an automobile radiator in diagrammatic section, the filler spout being shown in elevation, viewed from the direction of the driver's seat, the construction illustrating one form of my invention. Fig. 2 is a vertical sectional view of the parts shown in Fig. 1. Fig. 3 is a horizontal sectional view on line 3—3 of Fig. 2. Fig. 4 is a view similar to Fig. 1, illustrating a modified form of my invention. Fig. 5 is a horizontal sectional view taken on line V—V of Fig. 4. Fig. 6 is a vertical sectional view through a part of a filler spout, illustrating another modification of my invention. Fig. 7 is a top plan view of the

filler spout, shown in Fig. 6, with the cap removed. Figs. 8, 9 and 10 are figures similar to Figs. 1, 2 and 3, respectively, illustrating another modified form of the invention.

Referring to the drawings in detail, and particularly to Figs. 1, 2 and 3, the numeral 1 designates the radiator, which has an opening 2 in the top thereof. Secured to the top of the radiator is the filler spout 3, which is closed at the top by a suitable cap 4. Numeral 5 designates the usual vent pipe which projects up into the filler spout to carry off excess of water or any steam which may be formed.

In accordance with the form of my invention illustrated in these figures, I mount inside of the filler spout, as close to the wall thereof as is practicable, a thermometer or temperature responsive device 6, a window 7 being formed in the side of the filler spout toward the driver's seat to permit the instrument to be observed from such position. The thermometer may be of any suitable construction and may be mounted in any desired manner. Also the window may be a mere open slot as illustrated in these figures or may be glazed, as shown in Figs. 4 and 5. The thermometer is shown as of the ordinary glass tube type, containing an expandable liquid, and is mounted in a tube or casing 8, which is perforated at the lower end, as 9, to permit free access of heat to the bulb, while the upper part is cut away at 10, to permit the glass tube and liquid column to be seen. The glass tube is held in the metal casing in any suitable manner, as by the bodies of cement 11 and 12, the latter also serving to make an air and steam-tight connection between the glass tube and its casing. The casing may be attached in position in any suitable way, it being shown as provided with a screw threaded portion 13, which is screwed through a lug 14, projecting inwardly from the wall of the filler spout, the casing being further held in position by means of a lock nut 15. In order to prevent any steam finding its way into the radiator, from escaping through the window 7, and to prevent water from splashing out, the upper part of the thermometer and its casing are inclosed by a shell 16, the edges of which are held tightly in contact with the inner wall of the filler spout, the shell being attached in any suitable manner, as by the screws 17. This shell,

in addition to forming a chamber tightly sealed from the radiator, also provides adequate protection to the thermometer from funnels inserted into the filler spout when 5 filling the radiator or from other injury. The thermometer may be of such length as to project into the air space in the radiator above the normal water level therein, as set forth in my Patent No. 1,090,776, or, it may 10 project into the water to such depth as may be desired. In either case it will be seen that it gives temperature readings visible from the driver's seat of the car. The filler spout adjacent to the window therein may 15 be provided with suitable markings such as the arrows 18, by which the height of the column of liquid may be judged, and a designation such as the word "Steam" appearing on the plate 19, secured to the filler 20 spout above the window therein, may be provided, if desired, to call attention to the fact that when the column of liquid reaches the top of the window, steam is forming, a condition which should require the operator's 25 attention.

It will be seen that in the construction illustrated, I have provided a means for mounting an instrument to indicate the thermal condition of the engine in the most convenient 30 place for observation by the driver of the car, and yet in a place where the instrument is entirely out of the way, does not detract in any way from the appearance of the car, and is adequately protected from 35 possible injury. As the instrument preferably does not project beyond the normal outlines of the car, the appearance of the car is not changed in any particular. Neither is there danger of breakage, such as would 40 occur if the instrument had projecting parts. Moreover there is no projecting part which could in any way interfere with the clear view of the road on the part of the driver.

Figs. 4 and 5 illustrate a slightly modified 45 form of the construction shown in Figs. 1, 2 and 3. In this form the opening in the filler spout is closed by a glass 20, which is held against a shoulder 21 by an apertured plate 22. This plate may also be conveniently 50 employed as scale plate, if such is desired, it being illustrated as provided with the graduations 23.

Figs. 6 and 7, illustrate another modification of my invention, in which means are 55 provided for the ready insertion and removal of the thermometer which facilitates assembly, and permits the thermometer to be quickly replaced in case of injury. According to this construction, a well 25 is 60 formed inside of the filler spout adjacent to one wall thereof, such wall being provided with the aperture 7 as already described. An annular shoulder 26 forms the bottom of the well. The thermometer comprises a 65 casing 27, having a lower end 28 of reduced

diameter, which provides a supporting shoulder 29. The latter rests upon a packing 30 of rubber or the like, interposed between it and the flange 26, the casing being pressed down by a screw plug 31, screwing 70 into the top of the well, and preferably carrying an insert 32 of rubber or the like. It will be seen that this device can be assembled by merely inserting the thermometer casing, with the packing 30 in position 75 thereon, into the well and then screwing in the plug 31, which causes the casing to be tightly held in position.

Another modified construction is shown in Figs. 8, 9 and 10. In this construction, I 80 have shown the thermometer 6 mounted outside of the filler spout but in juxtaposition thereto. The casing 35 of the thermometer is preferably so shaped as to fit close to and virtually merge into the filler spout so as 85 to be as inconspicuous as possible and not to detract from the appearance of the car. The casing may be secured in position in any suitable manner, it being illustrated as having its lower end inserted in a hole 36 90 formed in the top of the radiator adjacent to the filler spout, and clamped in such hole by lock nuts 37, a suitable packing 38 being provided to prevent leakage. In this form of apparatus, as in that illustrated in Figs. 95 1, 2 and 3, the instrument does not project above the top of the filler spout, and therefore does not interfere with the application and removal of the filler cap, nor does it 100 change the appearance of the car, and it is protected by the filler spout against blows which might injure it.

While I have illustrated certain preferred embodiments of my invention, it will be understood that I do not intend to limit myself 105 to such embodiments, but that the construction may be changed and modified in a variety of ways.

Having thus described my invention, what I claim as new and desire to secure by 110 Letters Patent, is:

1. In apparatus of the character described, the combination with a vehicle radiator having a filler spout, of a thermometer mounted on the radiator, said thermometer having its thermally responsive part subjected to temperatures within the radiator and having its indicator part extending above the top of the radiator but not above the top of the filler spout and being located 115 in proximity to a wall of the filler spout, the parts being so constructed and arranged that the front of said indicator part is exposed to view, whereby the indicating part is readable and at the same time is protected 120 by the filler spout.

2. In apparatus of the character described, the combination with an automobile radiator having a filler spout, of a glass tube thermometer disposed vertically adja- 130

cent to a wall of the filler spout, the upper end of the thermometer being lower than the top of the filler spout and the bulb of the thermometer extending below the filler 5 spout into the radiator, said parts being so constructed and arranged that the indicating part of the thermometer is exposed to view.

3. In apparatus of the character described, the combination with an automobile radiator having a filler spout, of a glass tube thermometer disposed vertically adjacent to the rear wall of the filler spout, the upper end of the thermometer being lower than the 10 top of the filler spout and the bulb of the thermometer extending below the filler spout into the radiator, said parts being so constructed and arranged that the indicating part of the thermometer is exposed to view.

20 4. In apparatus of the character described, the combination with the filler spout of an automobile radiator, said filler spout having a window therein, of a thermometer mounted inside of said filler spout close 25 to the side wall thereof and adjacent to said window and visible therethrough, said window being formed in the rear wall of the filler spout.

5. In apparatus of the character described, the combination with the filler spout of an automobile radiator, said filler spout being provided with a window, of a thermometer supported inside of said filler spout and adjacent to said window and readable 35 therethrough, and an inclosing shell contacting with the inner wall of said filler spout around said window and inclosing said thermometer.

6. In apparatus of the character de-

scribed, the combination with an automobile 40 radiator having a filler spout, said filler spout having a window in one side thereof, of means forming a chamber separated from the interior of the radiator, into which said window opens, and a thermometer projecting 45 from the radiator into said chamber and readable through said window.

7. In apparatus of the character described, the combination with an automobile 50 radiator having a filler spout, of means forming a chamber adjacent to one side of said filler spout and sealed from the interior of the radiator, and a thermometer having a bulb located in the radiator and a tube extending into said chamber, said filler 55 spout being provided with a window opening into said chamber through which said thermometer may be read.

8. In apparatus of the character described, the combination with an automobile 60 radiator having a filler spout screw threaded at its upper end and having a cap screwing on said threaded portion for closing the spout, of a thermometer mounted adjacent to a side wall of said filler spout, means for 65 supporting said thermometer independently of said radiator cap, the temperature responsive element of said thermometer being subjected to temperatures within the radiator, and the upper part of said thermometer being located out of the path of said cap when 70 being screwed into position so as not to interfere with the attachment or removal of said cap, the parts being so constructed and arranged that the indicating portion of the 75 thermometer is exposed to view.

HARRISON H. BOYCE.
